CANDY SHOWCASE

Russell E. Young, Chesterton, Ind.

Application November 30, 1939, Serial No. 306,983

4 Claims. (Cl. 312—116)

This invention relates to a cabinet for displaying and preserving perishable edible articles, such as candy, for instance, the general object of the invention being to provide a cabinet having transparent side walls, a central chamber for receiving a cooling medium, such as ice or mechanical refrigeration, series of vertically spaced rotary supporting means and a plurality of removable trays carried by each series, for containing the articles, with a door for permitting access to the interior of the cabinet.

The invention also consists in certain other features of construction, combination and arrangement of the several parts, to be hereinafter fully described, illustrated in the accompanying drawings and specifically pointed out in the appended claims.

In describing the invention in detail reference will be had to the accompanying drawings where in like characters denote like or corresponding parts throughout the several views, and in which:

Figure 1 is a front view of the cabinet.

Figure 2 is a section on line 2—2 of Figure 1.

Figure 3 is a section on line 3—3 of Figure 1.

Figure 4 is a section on line 4—4 of Figure 3.

Figure 5 is a transverse sectional view through the cylinder and showing one of the rings.

Figure 6 is a top plan view of one of the rod carrying rings.

Figure 7 is a bottom plan view of one of the trays.

Figure 8 is a fragmentary vertical sectional view showing how a rod carrying ring is supported by a pair of ball race rings.

In these drawings, the letter A indicates the cabinet, which is preferably composed of eight sides, each side being formed of a frame 1 containing a transparent member 2. One of the sides forms a door 3, the hinges of which are shown at 4 and the latch at 5. A cylinder 6 passes through the longitudinal center of the cabinet and the bottom 7 of the cabinet has a hole therein through which the lower end of the cylinder passes, the bottom being supported from the lower end of the cylinder by a ring 8 on the cylinder and by an ornamental flange 9 which extends downwardly to a plane flush with the bottom of the cylinder. A ring 10 is connected to the lower end of the cylinder to widen this end so as to help the flange support the cabinet on a surface. The top of the cabinet is shown at 11 and upper and lower rings 12 receive between them the inner periphery of the top, said rings being attached to the cylinder, the upper end of which slightly projects above the top where it receives a removable cover 13. An

ornamental flange 14 extends upwardly from the top. The bottom of the cylinder is shown at 15 and a drain pipe 16 extends from this bottom through the flange 9 where it receives a cock 17.

A plurality of vertically spaced pairs of rings 18 is attached to the exterior of the cylinder and the rings of each pair are spaced apart to receive between them a rotary ring 19, anti-friction means 20 being placed between each ring 19, and the two rings 18. Radiating rods 21 are carried by each ring 19 for supporting the segmental trays 22. Each tray has a groove 23 in the lower edge of each side part and the two grooves of adjacent trays receive one of the rods, so that the rods removably support the trays and each tray of each series can be removed without disturbing the other trays.

Thus it will be seen, that any series of trays can be rotated to bring any tray of the series to a point where it can be reached through the door opening, so the tray can be removed or some of the contents thereof can be taken from the tray, and this without disturbing the other trays. Ice or refrigeration coil can be readily placed in the cylinder to keep the articles in the trays in good condition and the water from the melting ice or condensation from the coil can be drained from the cylinder by opening the cock 17.

The cabinet presents an attractive appearance and as the articles in all the trays can be readily seen through the transparent walls of the cabinet, sales of the articles will be increased.

It is thought from the foregoing description that the advantages and novel features of the invention will be readily apparent.

It is to be understood that changes may be made in the construction, combination and arrangement of the several parts, provided such changes fall within the scope of the appended claims.

What I claim and desire to protect by Letters Patent is:

1. A cabinet of the class described, comprising a plurality of flat sides each including a transparent member, one side forming a door, a vertically arranged centrally located cylinder passing through the cabinet and forming a chamber for receiving a cooling medium, spaced pairs of rings on the cylinder with the rings of each pair spaced apart, a rotary ring held between each pair of rings, radiating rods carried by each rotary ring, and a plurality of segmental shaped trays each having a quarter circular groove in the bottom edge of each side edge thereof and extending the entire length of said edge, the grooves of

each two adjacent trays receiving a rod whereby the trays are removably supported by the rods.

2. A cabinet of the class described, comprising a plurality of flat sides each including a trans-
5 parent member, one side forming a door, a vertically arranged centrally located cylinder passing through the cabinet and forming a chamber for receiving a cooling medium, spaced pairs of rings on the cylinder with the rings of each
10 pair spaced apart, a rotary ring held between each pair of rings, radiating rods carried by each rotary ring, a plurality of segmental shaped trays each having a quarter circular groove in the bottom edge of each side edge thereof and extend-
15 ing the entire length of said edge, the grooves of each two adjacent trays receiving a rod whereby the trays are removably supported by the rods, upper and lower flanges connected with the ends of the cabinet, a removable cover for the upper
20 end of the cylinder, and drain means connected with the bottom of the cylinder.

3. A cabinet of the class described comprising a plurality of flat sides each including a transparent member, a vertically arranged centrally located cylinder passing through the cabinet and forming a chamber for receiving a cooling medium, a
25

pair of vertically spaced rings on the cylinder, a rotary ring mounted on the cylinder between said pair of rings, radiating rods carried by said rotary ring, and a plurality of segmental shaped trays each having a groove in the bottom edge of each of its side edges, said grooves extending the entire length of said edges and engageable on the rods whereby each tray is supported by a pair of adjacent rods.

4. A cabinet of the class described comprising a plurality of flat sides each including a transparent member, a vertically arranged centrally located cylinder passing through the cabinet and forming a chamber for receiving a cooling medium, a pair of vertically spaced rings on the cylinder, 15 a rotary ring mounted on the cylinder between said pair of rings, radiating rods carried by said rotary ring, and a plurality of segmental shaped trays each having a groove in the bottom edge of each of its side edges, said grooves extending 20 the entire length of said edges and engageable on the rods whereby each tray is supported by a pair of adjacent rods, a removable cover for the upper end of the cylinder, and drain means connected with the bottom of said cylinder. 25

RUSSELL E. YOUNG.
